ELECTRONIC DEVICE

Otto Krenzien, Berlin-Siemensstadt, Germany,
assignor to Siemens & Halske Aktiengesellschaft, Berlin, Germany, a corporation of Germany

Application May 27, 1937, Serial No. 144,984
In Germany May 30, 1936

5 Claims. (Cl. 250—166)

This invention relates to electronic devices and in particular to method and means for increasing the efficiency of photoelectric secondary electron emissive amplifier tubes.

5 In a great number of practical applications of photo-tubes, the extremely small photo-electric currents released by impacting light are in need of large amplification before they are capable of insuring the desired actuation of electric load 10 circuits.

Such an amplification of photo-electric currents is accomplished in the so-called secondary-emission amplifiers or multipliers by that the primary electrons produced by virtue of photo-electric action upon a cathode are caused to impinge upon an electrode which presents as high as feasible a positive potential in reference to the photo-cathode with the result that secondary electrons are released therefrom. If the counter-electrode or plate at the points where the primary photo-electrons are caused to strike is coated with an electron-active substance in the form of a film or layer, say of alkali or alkaline-earth metals, then, in the presence of appropriate conditions, 20 such impacting primary electron will be able to produce say, from 8 to 10 secondary electrons, in other words, with the use of a single collecting electrode approximately 10 fold amplification by means of secondary electron emission is obtainable.

30 If the secondary electrons thus generated are, in turn, caused to impinge upon other similar plates, in which case each such additional gathering plate would be operated by a positive potential being a like amount above that of the respective preceding electrode or plate, then a corresponding boost of the electronic current or stream is obtainable at each such plate as a result of secondary emission. Yet, the general aim will be 35 to insure as high as feasible an initial current, that is, the current entering or put into the multiplier system.

With this end in view, according to the invention, one or more auxiliary electrodes are mounted 45 anteriorly of the photo-cathode, which, by the aid of a suitable electrical potential chosen therefor, are so made to act upon the electrons emanating from the photo-cathode that they will be united or concentrated upon the smallest possible 50 space. Such an arrangement makes it feasible to use photo-electrically active cathodes of essentially larger size than heretofore, while yet so combining practically all of the photo-electrically released electrons that they will enter the multiplier system. The photo-cathode of increased

size as here suggested makes it also possible to use incident light rays of greater aperture with a substantial increase in the initial energy.

In describing the invention in detail, reference will be made to the drawings, in which Fig. 1 shows a potential distribution between two electrodes and a secondary emissive amplifier for purposes of explanation, while Figs. 2 and 3 show the electrostatic contour potentials in electron devices embodying applicant's invention; and 10 Figs. 4, 4a, 5, 5a and 6 show the combination and modifications of applicant's invention wherein several stages of electron multiplication are shown.

The actions of auxiliary electrodes upon the 15 electrical field in front of photo-cathodes according to this invention may be seen in Figs. 1 to 3 which illustrate the results of experimental measurements to ascertain the distribution of the potential with various electrode systems, these 20 measurements being made in an electrolytic water vat as well known in the prior art.

Fig. 1 shows the construction known from the earlier art of a photo-cathode K with a cylindrical hollow electrode Z₁ being mounted anteriorly 25 thereof, with the provision of any auxiliary electrode, Z₁ being the first or input stage of an amplifier or multiplier being predicated for its operation upon secondary electron emission, and working at a positive biasing voltage in reference to 30 the cathode. A number of equipotential lines between K and Z₁ are indicated schematically by the solid lines, the numerical values indicated at the ends thereof giving the potential increments 35 in terms of volts as ascertained at the indicated places in comparison to the photo-cathode. The broken lines indicate the electric field lines along which the electrons which are released without any appreciable initial speed will travel in the electrical field, and which, as known, are at right 40 angles to the equipotential lines. The figure will make it clear that substantially only those electrons released on the cathode will enter the aperture O of the electrode Z₁ which are emitted from the central portions of the cathode between a₁ 45 and a₂, whereas such electrons as are emitted from the cathode outside the said solid angle will fail to strike electrode Z₁, indeed, will travel past the same.

Figs. 2 and 3, on the contrary, illustrate arrangements according to this invention which comprise an auxiliary electrode G interposed between the photo-cathode K and the multiplier electrode Z₁. From the position of the equipotential lines, for instance, in Fig. 2, it will be seen 55

that the utilizable (useful) solid angle over the cathode surface extends here as far as the boundary lines b_1 and b_2 , if the auxiliary electrode G is kept at cathode potential.

5 But as indicated by the equi-potential lines in Fig. 3, the conditions may be still further improved by that the whole cathode area is fully utilized, if electrode G is imparted a negative potential in reference to the cathode. The values 10 of the potentials indicated in Fig. 3 are referred to the auxiliary electrode G as zero potential, with the cathode K , for instance, being at a potential of 100, whereas the multiplier electrode Z_1 being the point of the field being at the highest 15 positive potential is identical with equipotential line 200.

A number of practical embodiments of multipliers according to this invention are schematically illustrated in Figs. 4 to 6.

20 Fig. 4 shows a cathode K in the form of a concave mirror or reflector and positioned obliquely in reference to the tube wall W , a photo-electrically active coat P covering the inner surface of the said cathode K , consisting, for instance, of a 25 surface film of caesium brought upon a metallic silver film acting as a substratum, and caesium oxide for the intermediary layer. An auxiliary grid G connected with the cathode is formed of three uprights which surmount the cathode surface to such a point that the parts thereof extending parallel to the mirror aperture are roughly at the same distance from the glass wall of the tube. In this embodiment the secondary-emission multiplier is of the double-stage type, 30 with growing potential in the direction of the anode. Each stage consists of a cylindrical concave electrode Z_1 and Z_2 respectively, of the well known L form. The primary electrons experience an accelerative effect towards Z_1 , they enter 35 at O into the concave electrode, and generate secondary electrons in the main axis at the specially activated knee or elbow part B_1 . The secondary electrons thus ensuing, in turn, are accelerated by Z_2 , and when they strike a similarly activated knee or elbow piece at B_2 they cause again the emission of secondary electrons. The stream of electrons amplified or multiplied in 40 the said manner finally reaches the anode A which is kept at the highest potential level. Potential is applied to the various stages by way 45 of leads brought through the press Q . The exciting light enters from the right-hand side and thus strikes the cathode; as can be seen from another elevation view of the cathode it is hardly impeded at all by the narrow auxiliary grid 50 strips. Inasmuch as the auxiliary grid G is at cathode potential, a large portion also of the photo-electric current emitted at points closer to the cathode edge or rim will still be directed 55 into the multiplier system, and these portions, as will be understood, would fly past the aperture of the system in the absence of the auxiliary grid of this invention.

In the exemplified embodiment shown in Fig. 5, auxiliary electrode G is united by stays S with the photo-cathode K , and it consists of a thin metal ring G which is raised above the median part of the concave cathode. The secondary-emission system in this instance comprises three multiplier stages Z_1 , Z_2 , Z_3 , the various concave cylinders being of the T type known in the prior art. The

highly activated places in each case are located directly opposite the inlet openings for the electrons, that is to say, at the inner portions of the cylindrical electrodes as indicated at B_1 , B_2 , B_3 . Also in this case the shadow thrown by the auxiliary grid upon the active photoelectric film will be immaterial. Moreover, the size of the cathode is sufficiently great so that the cylinder electrode Z_1 , in the case of light falling in from the left approximately on a horizontal level will 10 throw a shadow only upon a comparatively small portion of the cathode surface so that this loss may be readily accepted.

The arrangement shown in Fig. 6 differs from the embodiment Fig. 5 in that the auxiliary grid 15 G is no longer united directly with the photo-cathode K , but is brought into the tube by way of a distinct lead-in L and is insulated (separated) therefrom. In this manner, the auxiliary grid may be impressed with a markedly negative 20 potential in relation to the cathode so that the concentration (focusing) of photo-electrically released electrons is essentially improved.

Having described the invention, what is claimed is:

25 1. An electron device comprising a concave photoelectric cathode, a T-shaped secondary electron emissive electrode positioned in register with the cathode, a ring electrode positioned intermediate the cathode and the electrode and symmetrical with the cathode and an anode for collecting electrons from the secondary electron emissive electrode.

35 2. An electronic device comprising a photo-emissive concave cathode, a ring electrode positioned closely adjacent to and in register with the cathode and symmetrical therewith, and a secondary electron multiplier having a plurality of stages positioned to receive electrons from the photoelectric cathode said multiplier including an 40 anode for collecting the multiplied electrons.

3. An electronic device comprising a photo-emissive concave cathode, a ring electrode supported from and conductively connected to the cathode, and a secondary electron multiplier having a plurality of stages positioned to receive electrons from the photoelectric cathode said multiplier including an anode for collecting the multiplied electrons.

4. An electronic device comprising a photo-emissive concave cathode, a ring electrode positioned closely adjacent to and in register with the cathode and symmetrical therewith, and adapted to be maintained at a negative potential with respect to the cathode, and a secondary electron multiplier having a plurality of stages positioned to receive electrons from the photoelectric cathode said multiplier including an anode for collecting the multiplied electrons.

5. An electronic device comprising a photo-emissive concave cathode, a secondary electron multiplier having a plurality of stages spaced from said cathode, said multiplier including an anode and a focusing electrode closely adjacent to, in register with, and symmetrical with said cathode and positioned intermediate said cathode and said multiplier, and said electrode circumscribing the electron paths from said cathode to said multiplier.
